UNITED STATES PATENT OFFICE

ERROL I. BATEMAN, OF GULFPORT, MISSISSIPPI

RAILROAD CROSSING GATE

Application filed May 1, 1930. Serial No. 448,962.

This invention relates to an improved railroad crossing gate.

The object of the invention is to provide a guard at railroad grade crossings which will tend to eliminate any possibility of accidents to persons crossing the tracks and making it impossible for an automobile to cross when a train is approaching and, at the same time, to provide such a guard that will not be of inconvenience to motorists crossing when no train is dangerously near.

The action of the guard is such that it will cause the motorist to cross at a reasonable speed for his own comfort. The guard is preferably automatically controlled and may be connected with the block signal system of the railroad, so as to be regulated by the position of a train in respect to the crossing and to be unlocked by the departure of the train from the crossing and when the crossing is clear.

In the accompanying drawings:

Fig. 1 is a top plan view showing the application of the invention to a grade crossing; Fig. 2 is a transverse sectional view through one of the crossing guards; and

Fig. 3 is a vertical sectional view showing the gate actuated from both sides.

The railroad tracks are designated generally by the numeral 1 and extend across a road or street 2. This road preferably has a curbing 3 in the center to divide the lines of traffic crossing the tracks 1 in opposite directions, as indicated by the arrows in Fig. 1.

Arranged on each side of the curb 3 and on the approach side of the tracks is a gate 4, preferably constructed as shown in Fig. 2, with a cross bar 5 and a wire web or spring belt arrangement 6, both of which bar and web are suspended between upright posts 7. Both ends of the web 6 are connected with the posts 7 by suitable resilient connections such as springs 8. The bar 5 may carry suitable red reflectors or warning signals 9, if desired.

Arranged at each end of the gate 4 is a box or other suitable receptacle 10, into which the upright post 7 at that end extends where it is pivotally mounted as at 11. The lower end of the post carries a counter-weight 12 and

lock shields 13 on opposite sides of the counter-weight.

The upright post 7 is pivotally connected with a link 14, which connects the same with one end of a rocker 15 pivotally mounted as 55 at 16 within the casing 10. The opposite end of the rocker 15 is pivoted to a link 17, which pivotally connects the same with a tread 18 having one edge pivoted as at 19, so as to swing to an upright position. The tread 18 extends across the roadway at least half of the width of the roadway and a link arrangement similar to that shown in Fig. 3 is preferably provided at each end of the tread 18, connecting each of the upright posts 7 therewith. One of these only may be found sufficient, in which event the other may be omitted, or the one gate may be actuated from two treads 18 by providing two sets of links 14 and 17, and two rockers 15, as shown in Fig. 3. 70 This is desirable where the road is narrow and the treads extend the entire width.

The lower end of the post 7 or the counter-weight 12 is provided with a notch 20 in position to receive one end of a lever armature 75 21, as shown in Fig. 2, which armature is pivotally mounted as at 23 within the casing 10.

Arranged over the armature 21 is an electro-magnet 24 in position to attract the same when energized. An electric circuit is illustrated diagrammatically in Fig. 1 and designated by the numeral 25, and is shown connecting the electro-magnet 24 with the tracks 1, so as to control the actuation of the electro-magnets by means of the approach or departure of a train. If desired, either audible or visible signals, as at 26, may be disposed beside each gate 4, so as to indicate when it is safe to cross.

In using the invention, the gate 4 will normally be disposed in an upright position, as illustrated in the drawings, but with the magnets 24 deenergized, so that the armatures 21 will be lowered out of engagement with the notches 20. Upon an automobile approaching the crossing, the weight of the front wheels will depress the tread 18 and through the links 14 and 17 and the rocker 15, the gate 4 will be caused to swing to a lowered

position across the roadway, which allows the automobile to cross the tracks. After passing over the gate, the counter-weights 12 return the gate to an upright position.

5. Upon the approach of a train, the electric circuits 25 are closed, which causes an energizing of the magnets 24 to attract the armatures 21, to swing the same into notches 20 to lock the gate in an upright position. In 10 the event that the gate 4 has been moved over out of an upright position by the passing of an automobile, the guards 13 prevent the bar armatures 21 from being moved behind a portion of the upright post 7 or counter-weight 15 12 to prevent the gate from being returned to its normal upright position.

After the train is past clear of the crossing, the magnets are automatically deenergized to release the bar armatures 21 and permit the crossing of vehicles.

The invention is simple but provides an effective means of automatically controlling a crossing and to prevent vehicles from crossing a railroad track when a train is danger- 25 ously near.

I claim:

1. In a device of the character described, the combination with a crossing gate, of a platform in front of the gate and depressible 30 by the weight of a vehicle for actuating the gate, and an electrically actuated latch for direct contact with the gate to lock the same in a closed position.
2. In a device of the character described, 35 the combination with a crossing gate normally closed, of a platform arranged in front of the gate and depressible by the weight of the vehicle to open the gate, and an electrically actuated latch for direct contact with the gate to lock the same when a train is near the crossing.

3. In a device of the character described, the combination with a crossing gate, of supports for said gate, means for pivotally 45 mounting said supports, gravity actuated means for normally moving the gate to an upright position, and electro-magnetic means for engaging and locking the gate in an upright position.

- 60 4. In a device of the character described, the combination with a crossing gate, upright posts supporting said gate, pivotal means for said posts, means normally tending to move the gate to an upright position, at least one 55 of the posts having a notch therein, a lever in position to enter said notch and hold the gate in an upright position, and electro-magnetic means for automatically actuating said lever when a train is near the crossing.

65 5. In a device of the character described, the combination with a crossing gate, upright posts supporting said gate, pivotal means for said posts, means normally tending to move the gate to an upright position, at least one 60 of the posts having a notch therein, a lever in

position to enter said notch and hold the gate in an upright position, electro-magnetic means for automatically actuating said lever when a train is near the crossing, a tread arranged in front of the gate and depressible 70 by the weight of a vehicle, and means operatively connecting said tread with the gate normally tending to open the gate upon depression of the tread.

6. In a device of the character described, 75 the combination with a crossing barrier, a platform operatively connected with and for swinging the barrier out of restraining position, and an electro-magnetic latch for direct contact with the barrier to lock said barrier 80 in restraining position.

7. In a device of the character described, the combination with a crossing barrier, one or more supports for said barrier, pivotal means for said supports, means acting on the 85 support normally tending to hold the barrier in restraining position, said support having a notch therein, and electro-magnetic means for engaging the notch to lock the barrier 90 in restraining position.

8. In a device of the character described, the combination with a crossing barrier, one or more supports for said barrier, pivotal means for said support, a tread, linkage operatively connecting the tread with and for 95 swinging the barrier out of restraining position, said support having a notch therein, and electro-magnetic means for engaging the notch to automatically lock the barrier in restraining position.

9. In a device of the character described, the combination of a crossing barrier, means for holding said barrier normally closed, a platform arranged in front of the barrier and depressible by the weight of a vehicle for 105 opening the barrier, means operatively connecting the platform with the barrier, and an electrically actuated latch for direct contact with the barrier to lock the same in a closed 110 position.

10. In a device of the character described, the combination of a railroad crossing gate, means for holding said gate normally closed, a platform arranged in front of the gate and extending a substantial distance across a roadway, and depressible by the weight of a vehicle for opening the gate, means operatively connecting the platform with the barrier, and an electrically actuated latch automatically responsive to a condition of clearness of 120 a railroad track for direct contact with the barrier to lock the same in a closed position.

11. In a device of the character described, the combination of a pivotally supported railroad crossing gate, means for holding said gate normally closed, a platform arranged in front of the gate and extending a substantial distance across a roadway to be depressed by the weight of a vehicle for opening the gate, 125 means operatively connecting the platform 130

with the gate to swing the gate to an open position upon depression of the platform, and automatic latching means for direct contact with the gate to lock the same in a closed position.

12. In a device of the character described, a barrier having upright posts, pivotal means for the posts, at least one of the posts having a notch formed in a portion thereof to receive a locking latch, and one or more curved guards extending from a point adjacent the notch outwardly from the post to prevent engagement of the latch behind the post.

In testimony whereof I affix my signature.
